UNITED STATES PATENT OFFICE

DANIEL SCHWARTZ, OF CHICAGO, ILLINOIS

DESIGN FOR A RADIO STATION INDICATOR COVER

Application filed September 12, 1929. Serial No. 32,739. Term of patent 14 years.

To all whom it may concern:

Be it known that I, DANIEL SCHWARTZ, a citizen of the United States, residing at Chicago, in the county of Cook and State of Illinois, have invented a new, original, and ornamental Design for Radio Station Indicator Cover, of which the following is a specification, reference being had to the accompanying drawing, forming part thereof.

The figure is a perspective view of a radio station indicator cover showing my new design.

I claim:

The ornamental design for a radio station indicator cover as shown.

DANIEL SCHWARTZ.
